UNITED STATES PATENT OFFICE.

FRANK BAYLESS, OF SPRINGFIELD, OHIO.

RAILWAY-SWITCH.

SPECIFICATION forming part of Letters Patent No. 778,397, dated December 27, 1904.

Application filed March 17, 1904. Serial No. 198,531.

To all whom it may concern:

Be it known that I, FRANK BAYLESS, a citizen of the United States, residing at Springfield, in the county of Clark and State of Ohio, have invented certain new and useful Improvements in Railway-Switches, of which the following is a specification.

My invention relates to improvements in railway-switches, and it particularly relates to improvements upon the switch set forth in my Patent No. 750,334, issued January 26, 1904.

The object of my invention is to provide means for locking or holding the movable rails into the position to which they have been moved by the train-operated devices of the switch, so as to prevent displacement thereof by a passing train after the rails have been thrown to closed position by said train in the manner set forth in my said former patent.

A further object of my invention is to provide means to prevent the rebound of the movable switch-point from the main rail which might result from the shock incidental to its operation, and, further, to provide means to force the said switch-point back to its position against the rail in case of any such rebounding or to force the point up against the rail in the event the operating devices should not properly do so.

My invention consists in the constructions and combinations of parts hereinafter described, and set forth in the claims.

In the accompanying drawings, Figure 1 is a perspective view of a switch to which my invention has been applied. Fig. 2 is a bottom plan view of my device, showing the parts in their operated position. Fig. 3 is a device showing the parts in their normal position. Fig. 4 is a detail showing the position of the parts after they have been operated. Fig. 5 is a detail showing in full lines the device in a partly-operated position and in dotted lines the parts in normal and fully-operated positions, respectively. Fig. 6 is a detail of the stationary guide for the device, and Fig. 7 a view of one of the washers for the spring. Fig. 8 is a bottom plan view showing the parts in their normal or inoperative position.

Like parts are represented by similar letters of reference in the several views.

The main mechanism of the switch and the operation of the same are fully set forth and described in my said former patent and will therefore be but briefly referred to herein.

a represents the main rails of the line of track; *b*, the rails of a siding; *a' b'*, the movable or switch rails. The said movable rails are connected together by a bar *a'*, to which bar is attached the box or casing *c*. Extended through the casing and adapted to be normally connected thereto by spring-pressed plates *c'* is the ordinary hand switch-bar *c'*, connected to a hand-switch *c* for the purpose of operating the switch-rails in the usual way. Also extended through the frame or casing *c* is a train-operated bar *d*, connected to train-operated devices *e* for the purpose of operating said bar and in turn the switch-rails under certain conditions. This bar *d* is formed tapering at a point within the casing or frame *c*, as shown at *d'*, so as when operated to contact with the spring-pressed plates, and thus unlock the hand-operated switch-bar from the switch-rails, and is also provided with a shoulder *d''* near the point where it passes through the frame or casing, which shoulder will contact with the said frame or casing and move the same in the direction in which said bar *d* has been operated, so as to throw the switch-rails. In Fig. 2 I have shown a spring *d'* placed around the bar *d*, between the shoulder and the side of the frame or casing, to obviate any undue jar on the parts at this point. The train-operated bar is adapted to be operated by the said train-operated devices *e* in the manner described in my said former patent, so that in the event of a train approaching a switch which has been left open suitable contacting devices may be set on said approaching train to operate the said train-operated bar to close the switch.

In order that one of the switch-points or movable rails when operated by the train-operated devices shall be moved and firmly held close against the main rail to obviate any danger of derailment, I have provided the following-described devices: Pivots connected at *d* to

the train-operated bar d or to an extension d^6 thereof, as shown in the drawings, is an L-shaped arm f , one portion of which is provided with a slot f' , through which is extended the 5 upturned end f^2 of a stationary guide f^3 , which is secured to the under side of one of the ties. To the inner end of the slotted portion of the arm f is a collar f^4 , and loose on said slotted portion is a washer f^5 , adapted to fit 10 against the upturned end of the stationary guide f^3 . Around the slotted portion of the arm f and between the collar and washer is placed a coil-spring f^6 . When the mechanism of the switch is in its normal condition, the parts of the locking device are in the position shown in Fig. 3, with the spring extended. When the train-operated bar d is operated by an approaching train to throw the switch-rails to their closed position, 15 the movement of said bar will throw the devices to the position shown in Fig. 4, placing the spring under tension and causing it to exert an influence in the direction in which said bar d has been moved, and thus, by reason of the connection of said bar with the 20 movable or switch rails, through the medium of its shoulder and the casing or frame, as described, exerting a pressure upon the said switch-rails tending to hold them in their operated position. As shown in Fig. 5, the 25 point at which the spring is under the greatest tension is when the parts have completed about half their movement. After the parts have been fully operated it will be seen that 30 before they can again be restored to normal position the spring must be placed under greater tension up to a certain point. Thus any tendency to jar the rails from their position will be resisted by increasing tension of 35 the spring. The parts can be restored to normal position by pulling back the bar d by means of said train-operated devices.

While I have described my invention as relating particularly to the form of switch set 45 forth in my former patent, it is obvious that the invention might be applied to a switch of somewhat different construction, and I do not limit myself, therefore, in its application to the exact devices shown and described.

Having thus described my invention, I 50 claim—

1. In a railway-switch, the movable rail or rails thereof, train-operated devices adapted to be connected with said rail or rails to move 55 same from one position to another, and a normally inactive spring adapted to be placed under tension by the movement of said train-operated devices and exert its influence on said rail or rails to yieldingly hold same in 60 operated position, substantially as specified.

2. In a railway-switch, the movable rail or rails thereof, devices connected to said rail or rails adapted to be operated by a moving car or train to throw said rails from one position 65 to another, and means operated by said de-

vices to yieldingly hold the same, together with said rails, in their operated position, for the purpose specified.

3. In a railway-switch, the movable rail or rails thereof, train-operated devices normally disconnected from said rail or rails but adapted when operated to be connected therewith and move said rail or rails from one position to another, and means for yieldingly holding said operating devices, together with the rail 75 or rails, in operated position, for the purpose specified.

4. In a railway-switch, the movable rail or rails thereof, a train-operated bar adapted to be connected with said rail or rails when operated to move said rail or rails from one position to another, and a spring connected with said bar adapted, when said bar is operated, to be put under tension and exert an influence on said bar in the direction in which said bar 85 has been operated to throw said rail or rails, for the purpose specified.

5. In a railway-switch, the movable rail or rails thereof, a train-operated bar adapted to be connected with said rail or rails to throw 90 the same, when said bar is operated, from one position to another, a spring-support pivoted to said bar, a spring on said support, means connected with said spring-support to swing the same about its pivotal connection to a position substantially parallel with said bar when said bar is operated and to put the said spring under tension, substantially as and for the purpose specified.

6. In a railway-switch, the movable rail or rails thereof, a train-operated bar adapted to be connected with said rail or rails to move the same from one position to another when said bar is operated, a spring-support pivoted to said bar, a stationary guide slidingly connected to said support, and a spring between the pivoted end of said support and said guide, substantially as and for the purpose specified.

7. In a railway-switch, the movable rail or rails thereof, hand switch devices detachably connected to said rail or rails, train-operated devices adapted when operated to disconnect said hand switch devices and move said rail or rails from one position to another, and means connected with said train-operated devices 115 adapted to yieldingly hold the same, together with said rail or rails, in operated position, substantially as specified.

8. In a railway-switch, the movable rail or rails thereof, a hand switch device detachably connected to said rail or rails, train-operated devices adapted when operated to disconnect said hand switch devices and move said rail or rails from one position to another, and a spring connected to said train-operated devices adapted to be placed under tension when said devices are operated and exert an influence to hold said devices, together with the said rail or rails, in their operated position, substantially as specified.

9. In a railway-switch, the movable rail or rails thereof, an operating-bar connected to said rail or rails, and a normally inactive spring connected to said bar adapted when 5 said bar is operated to be put under tension and exert an influence on said bar to hold the same in its operated position, for the purpose specified.

10. In a railway-switch, the movable rail or 10 rails thereof, an operating-bar connected to said rail or rails, a spring-support pivotally supported by said bar, a spring on said support, and means, when said bar is operated, for swinging said support about its pivotal 15 point and placing said spring under tension, substantially as specified.

11. In a railway-switch, the movable rail or 20 rails thereof, an operating-bar connected to said rail or rails, a slotted arm pivotally connected to said bar, a stationary guide extending through said slotted arm, and a spring be-

tween the pivotal point of said arm and said guide, substantially as and for the purpose specified.

12. In a railway-switch, the movable rail or 25 rails thereof, a hand switch-bar normally connected to said rail or rails, a train-operated bar normally disconnected from said rail or rails, and devices, operated by said train-operated bar, to disconnect said hand switch-bar 30 from said rail or rails and move said rail or rails to a different position, and means operated by said train-bar to yieldingly hold said rail or rails in the position to which they have been moved by said train-bar devices, substantially as specified. 35

In testimony whereof I have hereunto set my hand this 12th day of March, A. D. 1904.

FRANK BAYLESS.
